UNITED STATES PATENT OFFICE.

EDWARD D. MACKINTOSH, OF BROOKLYN, ASSIGNOR TO PAUL PRYIBIL,
OF NEW YORK, N. Y.

BEARING-BOX.

SPECIFICATION forming part of Letters Patent No. 465,673, dated December 22, 1891.

Application filed March 25, 1891. Serial No. 386,311. (No model.)

To all whom it may concern.

Be it known that I, EDWARD D. MACKINTOSH, of Brooklyn, in the county of Kings and State of New York, have invented a new and useful Improvement in Bearing-Boxes, of which the following is a specification.

My invention relates to an improvement in bearing-boxes for shafting in which provision is made for adjusting the bearing up and down with great precision in order to secure its perfect horizontal alignment.

A practical embodiment of my invention is represented in the accompanying drawings, in which—

15 Figure 1 is a view of the box-frame showing the bearing therein in end elevation. Fig. 2 is a top plan view with the upper portion of the frame and adjusting-screw removed, and Fig. 3 is a view in vertical section taken 20 longitudinally through the bearing.

A represents the base of the box-frame, *a* the two side standards, and *a'* the top or cross-head. The part *a'* is removably secured to the upper ends of the standards *a* by means 25 of screws *B*. The lower half-bearing is represented by *C* and the upper half-bearing by *C'*. The lower half-bearing *C* is shown in the present instance as provided with laterally-projected lugs *c*, two upon each side, adapted 30 to embrace the opposite sides of the standards *a*, as clearly shown in Fig. 2. An adjusting-screw *D*, provided with a jam-nut *d*, is seated in the top *a'* and projects downwardly into position to hold the upper half-bearing *C'* in position and to prevent the upward displacement of the shaft.

The parts which I have thus far referred to are well known in the art, the particular forms which I have herein shown being selected for 40 the purpose of showing the practical application of the adjusting device which forms the particular subject-matter of my present in-

vention, and which is constructed and arranged as follows: In the base *A* of the frame there is formed a bevel-seat *e*, upon which a 45 bevel-faced support *E* rests, and upon which it is allowed a sliding movement to elevate and depress it. The upper end of the bevel-faced support *E* forms a seat on which the bearing *C C'* rests, so that as the piece *E* is 50 forced along up the incline *e* or allowed to recede down the said incline, the bearing and the shaft therein will be elevated or depressed. Through the side of the base *A* an adjusting-screw *F* extends, bearing at its inner end 55 against the side of the bevel-faced supporting-piece *E*, the said screw being provided with a jam-nut *f* to secure it in the desired adjustment. By turning the screw *F* in the direction to make it enter the base it will force the 60 bevel-faced support *E* upwardly along the incline *e*, and by turning it in the opposite direction it will lower the same.

It is obvious that the frame with its bevel-faced support and screw might be reversed to form a hanger-support instead of a standard-support, as herein represented.

What I claim is—

The combination, with the supporting-frame or hanger provided with an incline side and 70 the bearing having a movement therein relative to the frame, of a bearing-support having an inclined face adapted to engage the inclined seat upon the frame, and an adjusting-screw seated in the frame and having an engagement with the inclined-faced bearing-support to slide it along the inclined seat in the frame and thereby raise the bearing within the frame, substantially as set forth.

EDWARD D. MACKINTOSH.
